WILLIAM C. TROWBRIDGE, OF NEW YORK, N. Y.

Letters Patent No. 87,014, dated February 16, 1869.

IMPROVEMENT IN GAS-HEATERS.

The Schedule referred to in these Letters Patent and making part of the same.

To all whom it may concern:

Be it known that I, WILLIAM C. TROWBRIDGE, of the city, county, and State of New York, have invented a new and improved Gas-Stove; and I do hereby declare that the following is a full, clear, and exact description thereof, which will enable others skilled in the art to make and use the same, reference being had to the accompanying drawings, forming part of this specification, in which—

Figure 1 represents a vertical section of my improved stove.

Figure 2 is a plan or top view of the same.

Similar letters of reference indicate corresponding parts.

This invention relates to certain improvements on that kind of gas-stoves in which heated hydrocarbon-liquids are consumed.

The invention consists, first, in a new arrangement of pipes for conducting the oil to the flame with an object of collecting impurities and sediments, before the oil or its vapors reach the small orifice of the burner. In the apparatus now in use, this orifice is frequently clogged by the impurities of the oil, and the effectiveness of the stove thereby impaired.

The invention also consists in constructing the stove of open work, for the purpose of admitting air, to facilitate perfect combustion.

A, in the drawing, represents the flame-cup of my improved stove. It is made of cast-iron, or other suitable material, of suitable size and shape. If made for a small stove, with a single opening in the top plate, I prefer to make it of circular form; but for larger stoves, it will be correspondingly enlarged.

It is provided with a horizontal flange, *a*, which projects from its upper edge to the outside, and is perforated at its upper part.

The cup is supported on suitable legs, or standards, B B, which are fastened to its flange, *a*, or otherwise, as may be desired.

Upon the flange is placed a vertical plate, C, which supports the main stove-plate D, the latter being, by means of bolts E E, secured to the flange *a* as shown.

The plate C is perforated at suitable intervals.

The stove-plate has suitable apertures for cooking-vessels.

F is a pipe conducting the hydrocarbon-liquid from the reservoir to the cup A.

The reservoir is higher than the stove.

The pipe, however, is conducted under the stove, and then up, and through an opening in the plate C, into the stove, where it is turned down into the cup and then bent up again, its end carrying the burner *b*, as shown in fig. 1.

There is a plate, G, suspended from the upper arm of the pipe F, directly above the burner, for the purpose of distributing the heat.

The horizontal arm *c* of the pipe F, under the stove, serves to collect all sediments and impurities that are in the oil, and prevents them from reaching the burner.

The oil, at the starting of a fire, escapes through the burner and overflows, in a very small quantity, into the cup A, where it is ignited by applying a match.

The heat from this fire causes the oil in the pipe to be converted into gas, and this gas will, when it issues from the burner, immediately ignite, not falling into the cup.

When the fire has, for a short time, been in operation, the gas alone will burn, and there will be no flame on the bottom of the cup.

The perforations in the sides of the cup A, and in the ring C, allow atmospheric air to the flame, and facilitate combustion.

I claim as new, and desire to secure by Letters Patent—

1. Carrying the pipe F under the stove, substantially as described, for the purpose of collecting sediments and impurities, as set forth.

2. The combination of the perforated cup A, having the flange *a*, with the perforated plate C, top plate D, and pipe F, all arranged and operating substantially as herein shown and described.

WILLIAM C. TROWBRIDGE.
